UNITED STATES PATENT OFFICE.

JOHN WALLACE JAKEMAN, OF ALTRINCHAM, ENGLAND, ASSIGNOR TO LINOTYPE AND MACHINERY LIMITED, OF LONDON, ENGLAND, A BRITISH COMPANY.

SHEET-GRIPPER MECHANISM OF PRINTING MACHINES.

Application filed February 5, 1925, Serial No. 6,924, and in Great Britain February 19, 1924.

This invention relates to sheet-gripper mechanism such as that used in connection with the impression cylinders of printing machines, wherein the sheet grippers are secured to a shaft mounted in bearings in the cylinder, and means are provided for rocking the shaft to open and close the grippers at appropriate times during the rotation of the cylinder. It particularly relates to the known construction in which the spring pressure is applied to a cam fast to the gripper shaft and is directed along a straight line and serves both to supply the necessary gripping pressure between the grippers and the sheets, and to hold the grippers open and closed when the shaft is not under the influence of the mechanism by which it is rocked.

In one arrangement of this kind, the cam is so shaped that the pressure of the spring is directed against the cam along a line at substantially right angles to a radial line from the axis of the gripper shaft, and the operative portion of the cam is entirely concentric with the shaft excepting where there are provided recesses with which a roller, under the action of the spring, engages in order to lock the grippers in their open and closed positions.

The object of the present invention is to employ more advantageously than has been possible with the means heretofore available, the forces operating during the action of the mechanism, so that springs, lighter than those hitherto used for a corresponding gripper pressure, may be employed with a corresponding reduction of friction load on the gripper shaft bearings, the shaft-rocking mechanism being thereby enabled to operate more effectively and with less shock, while any tendency to disturb the cylinder by retarding or accelerating its rotation, is minimized and a higher running speed of the press rendered possible.

With these objects in view, the present invention contemplates the employment of a spring which exerts a force substantially radially towards the gripper shaft, in conjunction with means which resolve such force into components one of which exerts on the gripper shaft a turning moment which decreases rapidly as said shaft is rocked to open the grippers and immediately thereafter possesses a gradually varying value corresponding to some predetermined curve

of moments and just sufficient to complete, or assist in completing, the rocking of the gripper shaft to retain the grippers open.

The invention will now be described by reference to the accompanying drawings, in which:

Figure 1 is a plan partly broken away, of an impression cylinder provided with the improved gripper mechanism portions of which only are represented in this figure;

Figure 2 is a transverse section taken on line 2—2 of Figure 1, looking rightward of the last-named figure;

Figure 3 is a sectional side elevation of a part of Figure 2;

Figure 4 is a sectional view of part of the mechanism as seen from the left of Figure 2, and

Figure 5 is a diagram illustrative of typical curves of spring moments for the hitherto used slider-crank mechanism and the cam-actuated mechanism according to the present invention, these being represented respectively in full and dotted lines.

In the constructional form of the invention exemplified in the drawings, the gripper shaft 1, is rocked, in the well-known manner by a tumbler cam 2 rigidly attached to an outwardly extending end of said shaft, and adapted by its cam recesses 3, 4, to engage respectively with the studs (not shown) for opening and closing the gripper, which studs are, as ordinarily, moved axially into and out of their respective tumbler-engaging positions.

5 is one of the several grippers which are adjustably secured on the gripper shaft 1, 6 is the gripper pad appropriate to that gripper, and 7 the gripper pad shaft; the said pad and shaft are of any suitable known construction and, as they constitute no part of the invention, no further description thereof is considered necessary.

The gripping pressure is imparted to the grippers 5 through, preferably, two bent lever arms 8 each of which is pivoted, at one end, as by a shouldered bolt 9, to one of the internal webs 10 of the impression cylinder 11, and at the other or free end, as by a stud 12, to a spring rod 13 which is encircled by a helical spring 14. The spring rod 13, whose axis is virtually radial relatively to that of the gripper shaft 1, is free to slide axially through a partly spherical washer 15 which nests in a corresponding partly

spherical seating formed in an eye-bolt 16 rigidly secured to the appropriate cylinder web 10, while, near its otherwise free end, it is provided with a collar 17 adjustable thereon and between which and the washer 15, the spring 14 exerts its pressure.

Each of the lever arms 8 is forked at its free end, and between the tines receives not only the end of the respective spring rod 13 but also a roller 18 which is free to rotate upon the respective stud 12. This roller 18, under the influence of the respective spring 14, is caused to bear constantly against a cam 19 rigidly secured to the gripper shaft 1.

The desired variations in the turning moment exerted by each spring 14 on the gripper shaft 1 during the rocking of the latter, are secured by the shape of the cam 19 on which the respective roller 18 bears, and the cam may be designed to give the desired gripping pressure when the grippers 5 are closed and to ensure that, when the tumbler cam 2 engages the gripper opening stud, the force of the spring 14 opposing the rocking of the shaft will decrease rapidly. The shape of the cam 19 further ensures that, during the opening of the grippers, the spring moment, on passing the zero point, that is to say the point in the cycle of operations at which the moment assumes zero value, will reach a value just sufficient to overcome the friction of the gripper shaft 1 in its bearings and to bring the tumbler cam 2 into contact with a stop (not shown in the drawing) which determines the opening movement of the grippers 5. Consequently, when the grippers are closing, the force opposing the action of the tumbler cam 2 and the gripper-closing stud, will be small at the moment when these members come into engagement and thereafter through the compression of the spring, this force gradually increases up to a point at which it changes in direction to assist the rocking of the gripper shaft 1, after which the force increases rapidly to the maximum when the grippers are closed.

In the constructional form illustrated, each cam 19 is provided with an abutment 20 with which the respective roller 18 engages to retain the grippers in their closed position.

The advantages derived from the present invention over and above existing methods will best be appreciated from an inspection of the accompanying diagram (Figure 5), which shows by the full line α a typical curve of spring moments for the usual slider-crank mechanism and by the dotted line β a similar curve of spring moments for the cam-actuated mechanism according to the invention. In this diagram the ordinates represent the moment of the spring and the abscissæ angular displacement of

the gripper shaft from one of its extreme positions. The actual shape of the curve α depends upon the following factors:—

- (i) The length of the spring lever or crank; 70
- (ii) The stiffness or load per unit deflection of the spring;
- (iii) The "accumulation ratio" i. e. the ratio of the initial load to the final load to the spring; 75
- (iv) The ratio of the length of the crank to that of the spring rod, and
- (v) The angle between the centre line of the crank and the line of dead centres when the gripper shaft is in one of its extreme 80 positions.

Assuming that the item (v) is half the total angular movement of the gripper shaft, the area under the curve α above the line of abscissæ is equal to the area of the curve below that line and is a minimum when items (i), (ii) and (iv) are small and item (iii) approaches unity; the curve then approximates to a curve of sines. The area of the curve above the line of abscissæ 85 represents to some scale the work done by the gripper opening stud on the tumbler-cam in overcoming the moment of the spring, such work tending to retard the rotation of the cylinder; the area below the line of abscissæ represents to the same scale the work done by the spring in assisting the rotation of the gripper shaft, such work tending to accelerate the rotation of the cylinder by reaction between the tumbler-cam 90 and the gripper opening stud. The spring moment at the point X where the grippers are closed is the same for both mechanisms. The shaded area between the curves α and β shows the saving of work and consequent 95 wear upon the tumbler-cam and the studs effected by the employment of the mechanism according to the present invention instead of the slider-crank mechanism heretofore employed for the purpose. 100

To further elucidate the invention, it may be explained that the design of the cam 19 involves the following principle.

In any position of the mechanism, there are three forces meeting at a point which is 115 the centre of the cam roller 18.

These three forces are:—

- (1) The spring pressure acting along the line of the spring rod 13; 120
- (2) The pressure in the lever 8 acting along the line joining the centres of the cam roller 18 and the fulcrum pin 9, and
- (3) The reaction between the cam 19 and cam roller 18 acting along the line joining the centre of the cam roller to the centre of 125 curvature of the cam at the point of contact.

When the directions of three such forces and the magnitude of one of them are known, the magnitudes of the other two forces can be determined. 130

Further, the moment acting on the gripper shaft 1 is the product of the reaction between the cam 19 and its roller 18 into the vertical distance of the line of action of this force from the centre of the gripper shaft.

The object attained by a cam designed on this principle is to make both the magnitude of the reaction between the cam 19 and its roller 18 and the vertical distance of its line of action from the centre of the shaft 1 fall off rapidly as the latter turns from the position shown in Figure 2, so that the curve of moments approximates to some predetermined shape such as y in Figure 5.

Having described my invention, I declare that what I claim and desire to secure by Letters Patent is:—

1. The combination with a printing press cylinder, a gripper shaft mounted in said cylinder and adapted to be rocked, sheet grippers carried by the gripper shaft adapted to be opened and closed by the rocking of that shaft, and a spring adapted to exert a force substantially radially towards the gripper shaft, of means adapted to resolve such force into components one of which exerts on the gripper shaft a turning moment which decreases rapidly as said shaft is rocked to open the grippers and immediately thereafter possesses a gradually varying value corresponding to some predetermined curve of moments and just sufficient to complete, or assist in completing, the rocking of the gripper shaft to retain the grippers open.

2. The combination with a printing press cylinder, a gripper shaft mounted in said cylinder and adapted to be rocked, sheet grippers carried by the gripper shaft adapted to be opened and closed by the rocking of that shaft, and a spring adapted to exert a force substantially radially towards the gripper shaft, of means adapted to resolve such force into components, one of which exerts a turning moment on the gripper shaft said means comprising a cam so formed that the component exerting the turning moment acts through the cam along a line the perpendicular distance of which from the centre of the gripper shaft decreases rapidly as said shaft is rocked to open the grippers and throughout the remainder of the gripper-opening movement

gradually varies until the turning moment is just sufficient to complete or assist in completing the rocking of the gripper shaft to retain the grippers open.

3. The combination with a printing press cylinder, of a gripper shaft mounted in said cylinder and adapted to be rocked, sheet grippers carried by the gripper shaft adapted to be opened and closed by the rocking of that shaft, a spring adapted to exert a force substantially radially towards the gripper shaft, a cam mounted on the gripper shaft, a lever arm having one end pivoted to the impression cylinder, a rod to which the other end of the lever arm is pivoted and a roller carried by said rod and constantly held by the spring in contact with the cam, said cam being so formed that the perpendicular distance of the line of action of the force between the cam and roller decreases rapidly as the gripper shaft is rocked to open the grippers, and throughout the remainder of the gripper-opening movement gradually varies until the turning moment is just sufficient to complete or assist in completing the rocking of the gripper shaft to retain the grippers open.

4. The combination with a printing press cylinder, a gripper shaft mounted in said cylinder adapted to be rocked, and sheet grippers carried by the gripper shaft adapted to be opened and closed by the rocking of that shaft, of a cam mounted on the gripper shaft, a lever arm having one end pivoted to the impression cylinder, an axially slidable rod to which the other end of the lever arm is pivoted, and whose axis is virtually radial relatively to that of the gripper shaft, a roller carried by said rod, and a spring encircling said rod and constantly holding said roller in contact with the cam, said cam being so formed that the perpendicular distance of the line of action of the force between the cam and roller decreases rapidly as the gripper shaft is rocked to open the grippers, and throughout the remainder of the gripper-opening movement gradually varies until the turning moment is just sufficient to complete or assist in completing the rocking of the gripper shaft to retain the grippers open.

In testimony whereof I have affixed my signature hereto.

JOHN WALLACE JAKEMAN.
